UNITED STATES PATENT OFFICE.

CHRISTIAN MICKELSEN, OF BERKELEY, CALIFORNIA.

SAFETY-RAZOR-BLADE SHARPENER.

Application filed May 13, 1924. Serial No. 714,277.

My invention relates to razor sharpeners, and more particularly to safety razor blades sharpeners.

I am aware of numerous devices on the market for the sharpening of razor blades of the wafer type, but they are of complicated structure and hence expensive. It is my chief object to produce, in contrast to the above, a simple sharpener for this type of blade having but two simple moving parts, small and compact in structure, durable, inexpensive and efficient. One that is light in weight and portable, and adapted to rest horizontally upon a surface and be gripped by one hand and the moving parts be operated by the other hand moving to-and-fro, the blade sliding on the sharpening or stropping element and reversing at the end of the stroke.

With the above and other objects in view, my invention consists in certain novel features of construction, form and arrangement of parts. The accompanying sheet of drawings, forming a part of this specification, illustrates an embodiment of my invention, and what I claim as new, is particularly pointed out in the appended claims following this specification.

Figure 1 of the said drawings is a plan of my sharpener constructed in accordance with the invention and shows it in operative position, the handle being drawn toward the operator.

Fig. 2 is a sectional elevation of Fig. 1 along the line 2—2 thereof and looking in the direction of the arrows. The light dot-and-dash portion indicates the position the blade holder and blade will assume on the reverse stroke of the operating member.

Fig. 3 is an end elevation of Fig. 1 showing the blade in contact with the surface of the stone and the moving parts in engagement with the upper flange of the housing.

Fig. 4 is a plan of the movable members of the invention and shows to advantage the assembly thereof.

Adverting to the drawings: The numeral 5 indicates the oil or other sharpening stone or element of the device, and 6 a leather facing or equivalent stropping body. 7 is a housing or holder for the stone and preferably formed of sheet material, and having the remote end 8 closed and the near end 9 opened as shown and for a purpose to be later set forth.

To the holder 7 I preferably form with the

sides thereof a superstructure 10 in the shape of channels having the flanges in horizontal planes, 11 being the upper flange.

12 indicates the shaft of the blade holder and to which is mounted a pair of jaws. The jaw 13 is secured to the shaft as by rivet 14, and the other jaw 15 is hingedly attached to jaw 13 by hinge-pin 16. To the shaft 12 and jaw 13 is also secured, and by the same rivet 14, a spring clip 17.

To the jaw 13 is formed a pair of raised eyelets 18 for the mounting and positioning thereon of a razor blade 19 of the "Gillette" type, and the other jaw 15 has registering apertures 20 of larger bore for clearing the eyelets.

The ends 21 of the shaft 12 are adapted to be housed within the channels of the superstructure 10, and 22 represents a rubber or other ferrule slipped on the said ends for silent operation, if desired.

The operating member of my invention in the embodiment shown thereof, consists of a spring-wire frame 23 having its terminals loosely looped around the shaft 12 as at 24, the extreme ends 25 of the wire projecting outwardly, like fingers, and at right-angles to the side members of the frame. Additional fingers 26 and 27 are formed adjacent the finger 25, and the said fingers in combination with the end 21 of the shaft are designed to bear on the upper flange 11 of the channel structure when assembled. The shaft end 21 and middle finger 26 are adapted to bear on the under surface of the said flange and the other two fingers on the top surface thereof. 28 is the handle of the operating member and it is formed so as to project above the flange 11, Fig. 2, for the convenient grasping thereof by the forefingers.

To assemble the moving parts on the flange 11, the shaft 12 and frame 23 are inserted through the open end 9 of the housing 7, and the shaft ends 21 and fingers 25, 26 and 27 interpositioned on the said flange 11 as shown to advantage in Fig. 1.

In operation, the spring clip 17 and jaw 15 are raised and the razor blade positioned on the eyelets, then the handle moved to-and-fro. In one direction of movement the blade will draw across the stone as shown in full lines in Fig. 2, and in the reverse direction of the reciprocal motion, the blade will draw across the stone as shown by the dot-and-dash lines, same figure. It will be

noted that the shaft ends and fingers slide on the flange 11, and at the end of each stroke the shaft will oscillate and thereby reverse the blade. To strop the blade, simply slip the stone out of the holder from the open end 9 and present the stropping surface uppermost in the holder.

Having thus illustrated and described the preferred embodiment of my invention, 10 what I claim as new and desire to secure by Letters Patent is the following:—

1. A razor blade sharpener of the character described, comprising a sharpening element, a holder therefor having upper inwardly projecting flanges, a blade holder having a shaft, and an operating member attachable to the shaft near its ends and engageable with both surfaces of the said flanges, the said member adapted to be reciprocated along the surfaces of said flanges to support and carry the blade holder to and fro over the sharpening element, and said blade holder provided with a pair of jaws to position and hold a razor blade 25 therebetween for contact with the said element.

2. A sharpener for razor blades of the wafer type, comprising a flat sharpening stone, a holder therefor having channel-shaped side portions above the stone terminating in inwardly and opposed upper flanges, a blade holder consisting of a pair of jaws supported on a shaft and provided with means for engaging a wafer blade, 35 and a wire operating member having its extremities looped about the shaft near the ends thereof and terminating in fingers adapted to bear upon the upper surface of said opposed flanges, and adjacent said 40 fingers having additional fingers formed to bear against both surfaces of said flanges in cooperation with said first-named fingers for supporting the operating member and blade holder carried thereby in sliding engagement with the said flanges.

3. A razor blade sharpening device, comprising a block-like sharpening element having sharpening surfaces on its opposite sides, a housing for holding said element

and in which said opposed sharpening sides are reversible, said housing having a super-structure projecting above the surface of the sharpening element and along opposite sides of the housing, said structure forming a channel along each side of the housing terminating in a flat and relatively narrow guide strip as the upper wall of said channel, a blade holder, a shaft upon which said holder is mounted, the ends of said shaft being confined in said channels with freedom of reciprocation, and means connected to said shaft for reciprocating the same and wiping the blade carried by the holder over the uppermost surface of the sharpening element, said shaft-connected means having fingers projecting into the said channels and overlying the said guide strips for retaining the said shaft within the said channels and against the said guide strips.

4. A razor blade sharpening device, comprising a block-like sharpening element having sharpening surfaces on its opposite sides, a housing for holding said element and in which said opposed sharpening sides are reversible, said housing having a super-structure projecting above the surface of the sharpening element and along opposite sides of the housing, said structure forming a channel along each side of the housing terminating in a flat and relatively narrow guide strip as the upper wall of said channel, a blade holder, a shaft upon which said holder is mounted, the ends of said shaft being confined in said channels with freedom of reciprocation, and means connected to said shaft for reciprocating the same and wiping the blade carried by the holder over the uppermost surface of the sharpening element, said shaft-connected means comprising a spring-wire handle having fingers projecting into the said channels and overlying the said guide strips for interlocking the handle with freedom of reciprocation within the channels.

In testimony whereof I affix my signature.

CHRISTIAN MICKELSEN.
